[57] ABSTRACT

A portable heater-cooker is provided which includes a metallic container shaped as a pair of buckets and a cover which fits over the open top of the container, but which can be removed and fitted over the bottom of the container to form a stand for the unit. The unit can be merchandised complete with chemically treated charcoal or other suitable solid fuel. It is intended for the unit to be disposed after it has served its purpose, and after the solid fuel contained therein has been burned. disposable

3 Claims, 2 Drawing Figures

PATENTED NOV 6 1973

3,769,957

1
PORTABLE HEATER-COOKER**BACKGROUND OF THE INVENTION**

The portable heater-cooker of the invention provides a convenient unit which is ideally suited for hunting, fishing or camping trips, in that it can conveniently and easily be used for heating and/or for cooking purposes. The unit is in the form of a closed pail, or bucket, which contains, for example, solid fuel in the form of chemically processed starter charcoal and additional charcoal. The fuel in the unit can be ignited by a match in minutes, and it will burn for several hours.

In the utilization of the unit of the invention, the cover is removed, and legs are bent out from its top surface. The cover is then fitted over the bottom of the container to act as a stand. The solid fuel within the container is then ignited.

Appropriate sponge rubber packing may be provided at the top of the container to hold the solid fuel in place until the cover is removed. The unit may be encased in polyethylene wrapping, or the like, which is removed only when the unit is to be used. As mentioned above, the unit of the invention is intended to be disposable, and as many as may be required for any particular trip may be taken along the trip.

BRIEF DESCRIPTION OF THE DRAWING

FIG. 1 is a perspective representation of the heater-cooker unit of the invention in a closed form; and

FIG. 2 shows the heater-cooker unit of the invention opened and in readiness to perform its intended function.

DETAILED DESCRIPTION OF THE ILLUSTRATED EMBODIMENT

As illustrated in the drawing, the cooker-heater unit of the invention includes a container 10 which is shaped as a pail or bucket. The container has a usual handle 12 which is pivotally mounted in the side wall of the container, and which has a looped configuration, as shown.

A cover 14 is provided which fits over the upper rim of the container, when the container is in the closed condition of FIG. 1. The cover has a plurality of legs 16 which are normally folded into the plane of the top surface of the cover. However, when the cooker-heater unit is to be used, the cover is removed, and is snapped over the bottom of the container 10, as shown in FIG.

2. The legs 16 are turned out, as also shown in FIG. 2, so that the cover may form an appropriate stand for the unit.

As shown in FIG. 2, the unit has an upper rim 18 which is intended to support a cooking utensil. Appropriate air holes 20 are formed in the upper rim.

The container is normally filled with solid fuel, such as charcoal 22, and specially treated starter charcoal, so that ignition may be accomplished easily and efficiently.

The entire unit is intended to be disposable. It is purchased in the form shown in FIG. 1 with the solid fuel contained within the container 10, and packed, as suggested above. The entire unit may be appropriately wrapped, as also suggested above.

At the camp site, the unit is opened, and it may be started easily by a match, and the charcoal will begin burning efficiently within four or five minutes. The solid fuel heat produced by the illustrated unit has no odor, as is the case when liquid fuel is used. The unit will burn, for example, for about four hours under usual conditions, and with intense heat.

It will be appreciated that although a particular embodiment of the invention has been shown and described, modifications may be made. It is intended in the claims to cover the modifications which come within the spirit and scope of the invention.

What is claimed is:

1. A cooker-heater unit comprising: a container having a closed bottom and an open top, and further having an upper rim to serve as a support for a cooking utensil, said upper rim having air holes formed therein; a cover for said container having legs formed therein in position to be turned out from the plane of the surface thereof, said cover being adapted to fit over the open top of said container and form an enclosure therefor and being further adapted to fit over the bottom of said container with said legs being turned out from the plane thereof so as to serve as a stand for said container.

2. The cooker-heater unit defined in claim 1, and which includes a wire loop handle pivotally mounted on said container.

3. The cooker-heater unit defined in claim 1, in which said container and said cover are formed of metal, and said cover is configured to fit over the top rim of said container in a friction fit therewith.
